UNITED STATES PATENT OFFICE.

JOHN WILLIS GARDNER, OF QUINCY, ILLINOIS.

VALVE STRUCTURE FOR AIR-COMPRESSORS AND THE LIKE.

1,107,284.

Specification of Letters Patent. Patented Aug. 18, 1914.

Application filed June 2, 1910. Serial No. 564,556.

To all whom it may concern:

Be it known that I, JOHN WILLIS GARDNER, a citizen of the United States, and a resident of Quincy, in the county of Adams and State of Illinois, have invented certain new and useful Improvements in Valve Structures for Air-Compressors and the like; and I do hereby declare that the following is a full, clear, and exact description thereof, reference being had to the accompanying drawings, and to the letters of reference marked thereon, which form a part of this specification.

This invention relates to improvements in valve structures.

As shown and described herein, it is applied to the intake and discharge valves of air compressors and its use in such devices is especially advantageous.

The invention consists of the matters hereinafter described and more particularly pointed out in the appended claims.

In the drawings:—Figure 1 is a vertical section through an air compressor provided with my improvements. Fig. 2 is a partial vertical section through the cylinder head shown on the scale of a full sized compressor. Fig. 3 is a top plan view of the cylinder head with the outer retaining cap removed. Fig. 4 is a perspective view of the valve ring.

The drawings, Figs. 1 to 4, inclusive, illustrate an air compressor of the vertical type provided with my improved valve structures. Said air compressor is of any usual construction as to its main features and comprises a cylinder, a piston working in said cylinder, and a crank shaft, crank arm and connecting rod adapted to drive the piston.

With more particular reference to Fig. 1, 40. 10 is the cylinder; 11, the piston; 12, the connecting rod hinged to the piston; 13, the fly wheel; 14, the air supply chamber from which the air is drawn into the cylinder; 15, a water jacket to cool the cylinder; and 16, 45 an air discharge chamber into which the air is discharged from the cylinder in the action of the compressor and from which it is led by means of a pipe 17 to a tank or other receiver; and 18, the cylinder head.

The cylinder head is made in two parts, 18^a, 18^b, (see Fig. 2). The bottom member 18^a consists of a flat disk 19 which rests against an annular shoulder 11^a formed within the end of the cylinder. A centrally disposed, externally threaded, annular boss 19^a is formed on the upper surface of said

disk. The top member 18^b consists of concentric, radially spaced rings 21 connected by radial ribs 22. The outer ring 20 is of the same diameter as the disk 19 and both outer and inner rings rest on said disk. The inner ring 21 is of slightly larger diameter than the annular boss 19^a on the bottom member 18^a and is internally screw-threaded to receive the external thread of said boss.

23 indicates a set of annularly arranged narrow ports formed in the disk 19 between the inner and outer rings 20, 21 of the top member 18^b of the head. Above said ports and between the rings 20, 21 is located a stop rib or ring 24 which is rigidly connected to the radial ribs 22. Between the top of the disk 19 and the lower face of the circular stop 24 is located a flat, thin valve ring 25 which is adapted to seat on the top of the disk 19 and close the ports 23. The lift of the valve ring is limited by said circular stop.

The valve ring 25 is made from a very thin, flat sheet of tempered metal having great elasticity. Such metal as saws are made from is an example of material from which the valve rings are preferably made. The ports 23 are quite narrow in a direction radial of the cylinder head and the valve ring projects at each side of said ports. The lower face of the rib 24 is located but a short distance above the face of the disk 19, the required lift of the valve being small. The lower face of said rib is narrower than the width of the valve ring 25, which projects beyond it at each side, and is preferably serrated or otherwise roughened, as indicated at 24^a, to prevent the valve ring from sticking to it.

Owing to the resiliency of the valve ring and to the thinness of the metal from which it is made, it is not necessary to face the surface of the disk 19 forming the valve seat, and an air-tight joint is formed without grinding the valve seat and regardless of the condition of such seat, as to the presence of grit or other dirt. As the valve ring projects at both sides beyond the stop-ring 24, a large area of the valve is exposed to the pressure in the receiver, so that the valve is instantly seated at the end of the compression stroke without the use of springs or other similar closing means. By reason of the lightness of the valve ring and of its short lift the valve operates noiselessly without shock or jar, even when the compressor

is run at very high speed as, for example, from 400 to 600 revolutions per minute.

The cylinder head is retained in place by means of a coiled spring 26 which rests at its lower end in a recess 26^a formed in the radial ribs 22 and at its upper end engages within a socket 27^a formed in the underside of a cap 27 secured in the usual manner to the outer wall 10^a of the cylinder. By this construction the cylinder head may yield in case of any obstruction between the head and the piston, thus obviating any danger of breaking or otherwise damaging the parts.

A valve construction similar to that provided in the cylinder head is located in the piston for controlling the intake of air into the cylinder. The piston 11 is hollow, containing a chamber 11^a and is provided with an annular space 11^b surrounding the piston body and below the chamber 11^a which communicates by large ports 11^c with said chamber. Longitudinally spaced sets of annularly arranged ports 30, 31, in the cylinder wall connect the air supply chamber 14 with the cylinder, and are adapted to admit air to the annular space 11^b surrounding the piston. The piston head is formed in two parts,—an inner member 32 made rigid with the cylinder proper which incloses the upper end of the chamber 11^a, and an outer member 33 in the form of a flat disk provided with a centrally disposed, externally threaded boss 33^a which is screwed into an internally screw-threaded recess or opening 32^a in the part 32. An annular projection 32^b is formed on the top face of the member 32 and against this projection rests the flat disk 33. The member 33 is of nearly the internal diameter of the cylinder so that it projects radially beyond the annular projection 32^b. The two members 32, 33 are thus separated by an annular space 32^c which opens into the cylinder about the edges of the disk 33. A set of annularly arranged narrow ports 35, formed in the member 32, connect the chamber 11^a with the said annular space 32^c and a set of annularly arranged narrow ports 36 formed in the disk 33, radially within the ports 35, connect the cylinder with the said space 32^c. Thus air entering the annular space 32^c from the chamber 11^a in the piston may escape to the cylinder about the edges of the disk 33 and also through the ports 36 formed in said disk.

37 is a flat valve ring made from a sheet of tempered metal like the valve ring used in the cylinder head. It is located in the annular space 32^c between the two parts of the piston head in position to close the ports 35. Said valve seats on the member 32 of the piston head and its lift is limited by the disk 33 which acts as a stop. The valve ring 37, as before, is substantially wider than the ports 35.

65 During the compression stroke of the pis-

ton, after the piston has passed the upper set of ports 30, the air inclosed between the piston and the cylinder head will pass about the edges of the disk 33 and through the ports 36 and will thus come to bear on the 70 valve ring 37, and hold it seated in a position covering the ports 35, thereby preventing the air from the cylinder from passing into the chamber 11^a. The compression of the air in the cylinder will cause the 75 valve ring 25 to lift and permit the compressed air to pass from the cylinder into the receiving chamber 16 in the usual manner. Upon the return stroke of the piston the pressure of the air in the receiver will 80 immediately close the valve ring 25 upon its seat, covering the ports 23 and the pressure of the air in the supply chamber 14, which now communicates freely through the ports 30 and 31, the annular passage 11^b and the 85 chamber 11^a, with the ports 35 in the piston head, will lift the valve ring 37 to uncover said ports 35, whereupon the air may readily escape at each side of the valve ring through the ports 36 and about the edges of 90 the disk 33 into the cylinder.

The ports 30, 31 are separated longitudinally by a distance greater than the length of the piston from the annular space 11^b to the top of the member 32 of the cylinder 95 head so that at the end of the return stroke, when the piston covers the lower ports 31, it uncovers the upper ports 30. By this arrangement the inrush of air during the return stroke to the piston chamber 11^a is first 100 partially cut off by closing the upper ports 30 and then entirely shut off by closing the lower ports 31. As the ports 31 are closed, the upper ports 30 are opened above the piston head, thereby permitting air to enter 105 the cylinder directly from the supply chamber and the valve ring 37 to drop into position covering the ports 35 in readiness for the compression stroke.

As described and illustrated above, the 110 ports covered by the flat thin valve members are narrow and said valve members themselves are in the form of rings. Neither of these features are essential as the valve ring may be of any shape provided it is made of 115 flat, thin, elastic metal, and the ports may be of any width to give the required port-area; provided the valve seat has sufficient superficial area for the flat, thin, elastic valve member to close upon, and is so constructed as to furnish narrowly separated supports to prevent the thin, movable valve member from bending under the pressure exerted by the air or other fluid against it.

I claim as my invention:—

1. A valve structure, comprising a ported seat, a stop spaced above said seat, a free, floating, unguided valve ring made of thin, flexible sheet metal and of dimensions such as to require but little lift, said valve ring 120

being adapted to move between said seat and said stop to open and close the passage through said seat and being so located as to permit discharge at both its inside and 5 outside edges.

2. In an air compressor, in combination with the cylinder and a discharge chamber located without said cylinder, a wall interposed between said cylinder and discharge 10 member, said wall being provided near its marginal edge with annular separated slots forming ports, a floating movable valve ring consisting of a thin flat annulus of flexible elastic metal adapted to seat on 15 said wall above said slots and to extend radially beyond the inner and outer edges thereof so as to cover the same, an annular stop member rigidly supported from without said wall and movable valve ring in 20 line with said annular slots, said stop limiting the upward movement of said ring yet allowing a rotary and limited lateral shifting movement of the same, said stop having each lateral edge thereof spaced inwardly 25 from the lateral edges of said movable valve ring in any position of the same, whereby the fluid passing through said annular slots, passes around each lateral edge of the valve ring member and each lateral edge of the 30 annular stop member, thus exposing the lateral edges of said valve ring member to the pressure of the fluid in the discharge mem-

ber so that said valve will readily close on its seat.

3. In an air compressor, in combination 35 with a cylinder, a wall closing the end of said cylinder comprising a flat disk provided with a centrally disposed, externally screw-threaded boss on its outer face, concentric, radially separated, rigidly connected 40 rings bearing against the outer face of said disk, the inner ring being provided with screw-threads to receive said boss, said disk being provided with a plurality of annularly arranged ports intermediate said rings, a 45 flat valve ring of thin, elastic metal adapted to close said ports, a stop ring rigidly supported between said concentric rings a short distance from the surface of said disk, said stop ring having a face adapted to be engaged by said flat ring and limit the movement thereof, said face being narrower than said valve ring, and said disk being provided with narrowly separated supports for 50 said valve ring. 55

In testimony, that I, claim the foregoing as my invention I affix my signature in the presence of two witnesses, this 27th day of May A. D. 1910.

JOHN WILLIS GARDNER.
